Primary Examiner — Omeed Agilee(57) **CLAIM**

The ornamental design for a tray for medical use as shown and described.

DESCRIPTION**1.1** : Bottom view in perspective**1.2** : Bottom view**1.3** : Top view in perspective**1.4** : Top view**1.5** : Large-side lateral view**1.6** : Small-side lateral view

Packaging tray provided with magnetic elements adapted for gripping and comprising 16 clip-type fasteners, each for locking a cap for a bottle for medical use.

The broken lines depict portions of the tray for medical use that form no part of the claimed design.
